UNITED STATES PATENT OFFICE.

PLATT L. WISE, OF PORTLAND, OREGON.

SUBAQUEOUS CONSTRUCTION.

Application filed September 16, 1922. Serial No. 588,661.

This invention relates to a method and means of constructing a tunnel, and the like, the general object of the invention being to construct such structures upon floating bases 5 which form a part of the completed structures at the places where they are to be located.

Another object of the invention is to make the structure hollow so that it will float, 10 thus permitting it to be towed to the place where it is to be sunk and permitting most of the work to be done in the open and above water.

Another object of this invention is to 15 make a cellular constructed tunnel giving each class and direction of traffic a separate compartment, thus making it easier to control the traffic and to ventilate the structure.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying drawings wherein like characters denote like or corresponding parts throughout the several 30 views, and in which:—

Figure 1 is a plan view of the invention showing a tunnel being constructed in accordance therewith, the top of the tunnel not being in place.

Figure 2 is a horizontal sectional view 35 through one of the tunnel sections.

Figure 3 is a plan view showing how the structure is moved to a place where it is being sunk.

Figure 4 is a diagrammatic view showing 40 the structure being sunk into place.

Figure 5 is a cross sectional view showing a tunnel and portion of a wharf.

Figure 6 is an end view of a tunnel section.

In carrying out my invention I build a 45 base 1 of timbers 2 which are fastened together to form a raft. Cement forms 3 are then erected on this raft and concrete 4 placed in the forms. This concrete forms 50 the walls of the structure and bulkheads 5 are placed at the ends of the structure to keep out the water. Other bulkheads 6 are placed intermediate the ends of the structure to divide the same into compartments 55 which may be used to hold the ballast water while the structure is being built and to

prevent any sudden shifting of the water that is used in sinking the structure. The bulkheads are strengthened by the braces 7. The outer walls of the structure and the 60 bulkheads at the ends thereof form an entirely enclosed structure which is similar to a ship whose entire cargo capacity has been used in strengthening and stiffening the same. The end bulkheads must be built 65 strong enough to withstand the pressure at whatever depth the structure is to be sunk. I form in the tunnel as a roof of the ballast water compartment at the bottom thereof, a longitudinal way with an exit at the terminal 70 wharf, as shown in Figure 5. Air and water pipes 8 are provided for pumping air or water into or out of the structure. After the structure is nearly completed it is towed or otherwise moved to the place where it is 75 to be sunk and then by pumping out the air and pumping in water the structure is sunk to its bed which has been prepared beforehand. The structure may be formed in sections and after the sections have been put 80 in place cement or concrete is placed between the adjacent ends of the sections and after this is hardened the bulkheads are removed and the cement dug away so as to provide communicating openings between 85 the sections. This cement is shown at 9 in Figure 5.

From the foregoing it will be seen that the structure is built as a floating unit, this foundation being built from timbers floating 90 on the surface of the water, without the aid of any launching ways or other auxiliary structures. This foundation becomes a part of the structure and is sunk with the structure. The structure as it is being built forms 95 a boat, the ends of which are formed by bulkheads. The structure is of cellular construction, the compartments being formed by interior walls and bulkheads. The structure is kept at an even depth of flotation by 100 pumping in water and distributing the water in the different compartments to keep the structure trim as it is being built. This structure can be built at any desired point and then moved to the point where it is to be sunk. This structure will have the strength of a similar structure on land but its weight is very little more than that of the water or mud that it displaces so that it needs no foundation for itself and is 105 capable of acting as a foundation for other structures. Nearly all of the work can be 110

done in the open without the use of divers, or the doing of the work under water.

Figures 3 and 4 show how the structure can be towed by barges, shown at A, to the place where it is to be sunk. Ranging masts B can be placed on the structure for facilitating its positioning.

Figure 5 shows a tunnel and a wharf placed over the land section of the tunnel 10 with stairs leading from the wharf into the tunnel.

It will of course be understood that any form of structure can be built in accordance with the invention, the general idea being to 15 build the structure as a floating foundation and to provide bulkheads for making the structure like a ship so that it will keep afloat until it is desired to sink the same.

It is thought from the foregoing description that the advantages and novel features 20 of my invention will be readily apparent.

I desire it to be understood that I may make changes in the construction and in the combination and arrangement of the several 25 parts, provided that such changes fall within the scope of the appended claims.

What I claim is:—

1. A method of forming a sub-aqueous tunnel consisting in forming at the water-line tubular concrete sections forming an 30 integral unit of independent cells adapted

to hold water ballast below a way level, said section being water-tight at the ends, towing the buoyant section to the tunnel site, pumping water into the cells to lower the section into close alignment with a preceding section, forming a concrete seal at the junction and finally puncturing the section ends adjacent each joint. 35

2. A method of forming a sub-aqueous tunnel consisting in forming at the water-line, a plurality of parallel sections of cellular character below a way level, said sections forming a unit water-tight at the ends, floating it into adjacent position to a neighboring section, pumping in water to the cells, sealing the joints and puncturing the seals at the joints. 40

3. A sub-aqueous tunnel, comprising a plurality of integral concrete sections, each section having a concrete way supported on transverse watertight partitions rising at intervals forming water ballast cells, puncturable concrete diaphragms at the ends of each section, pipes in each section for supply of water to the cells to sink the section to the tunnel bed, the partitions being of such height as to afford water ballast to hold the sections in place, and watertight seals at the several adjacent section joints. 45

In testimony whereof I affix my signature. 50
